UNITED STATES PATENT OFFICE.

WILLIAM C. LORENZ, OF ALEXANDRIA, MINNESOTA.

STEERING-GEAR ATTACHMENT FOR AGRICULTURAL MACHINES.

989,168.

Specification of Letters Patent. Patented Apr. 11, 1911.

Application filed March 2, 1910. Serial No. 546,972.

To all whom it may concern:

Be it known that I, WILLIAM C. LORENZ, a citizen of the United States, residing at Alexandria, in the county of Douglas and 5 State of Minnesota, have invented a new and useful Steering-Gear Attachment for Agricultural Machines, of which the following is a specification.

This invention relates to steering gear for 10 threshing machines and other agricultural machines adapted to be drawn by traction engines.

One of the objects of the invention is to provide mechanism of this character utilizing 15 a coupling pole, said pole having means whereby it can be shifted relative to the structure to which it is connected and thus change the direction of movement of said structure.

20 A further object is to provide simple means for actuating the pole or tongue, said means being easy to operate and durable in construction.

With these and other objects in view the 25 invention consists of certain novel details of construction and combinations of parts hereinafter more fully described and pointed out in the claim.

In the accompanying drawing, which is a 30 perspective view of the device, the preferred form of the invention has been shown.

Referring to the drawing by characters of reference, 1 designates a cross beam adapted to be connected to the agricultural 35 machine by means of eye-bolts 2 or the like preferably located adjacent the ends of the beam. Upper and lower metal strips 3 and 4 are secured upon the upper and lower faces of the beam 1 at the center thereof and 40 extend forwardly at right angles to the beam, the front end of these strips being attached to coupling plates 5 which are, in turn, secured to rearwardly diverging braces 6 also attached to the upper and lower faces 45 of the beam, these braces being connected to the end portions of said beam.

Arcuate guide rails 7 extend between the strips 3 and 4 and are secured at their ends to the braces 6, these rails also extending between the upper and lower braces. Guide 50 sheaves 8 are journaled between the ends of the rails and are for the purpose hereinafter set forth. A coupling pole or tongue 9 is fulcrumed, as at 10, between the front end 55 portions of the strips 3 and 4 and the rear end of this pole is mounted to slide between

the rails 7, it being understood that said rails are concentric with the fulcrum 10. One or more reinforcing plates 11 may be secured longitudinally upon the pole 9 and eye-bolts 12 may be attached to the sides of the pole adjacent the rear ends thereof. The ends of a cable 13 are fastened to these eye-bolts, said cable being extended partly around the sheaves 8 and being secured, at 65 an intermediate point, to a shaft 14 which is arranged vertically within the rear portions of the strips 3 and 4 and is provided at its upper end with a worm gear 15. The cable is so wound upon the shaft that, when 70 the shaft is rotated in one direction, a portion of the cable will be paid out, while the remaining portion will be wound upon the shaft. Supports 16 are mounted on the beam 1 and on the strips 3 and one of the rails 7 75 and a shaft 17 is journaled upon them and carries a worm 18. The crank 19 may be located at one end of the shaft to facilitate the rotation of the worm and the resultant rotation of the gear 15 with which the worm 80 meshes. A locking pin 20 may be removably mounted within openings 21 in the strips 3 and 4, this pin being adapted to be inserted through an opening 22 in the pole 9 when 85 said pole is brought into position between 90 and parallel with the said strip 4.

It is to be understood that the front end of the pole may be connected to a traction engine or the like, while the beam 1 is to be attached to the machine to be drawn by the 95 engine. When it is desired to steer the drawn machine, it is merely necessary to rotate the worm 18 and this will correspondingly rotate the gear 15. Cable 13 will therefore be shifted so as to swing the pole either 95 to the right or to the left, according to the direction in which the shaft 17 is rotated.

It will be seen that the structure is very 100 simple, durable and efficient, and can be readily operated.

Various changes can of course be made in the construction and arrangement of the parts without departing from the spirit or sacrificing any of the advantages of the invention as defined in the appended claim.

What is claimed is:—

A steering attachment including a cross beam, upper and lower strips extending forward at right angles to the beam and connected thereto, coupling plates connected to the front ends of the strips, rearwardly diverging braces connecting said plates to the 110

upper end lower faces of the beam at the ends thereof, arcuate guide rails extending between the forwardly extending strips and secured at their ends to the braces, guide 5 sheaves journaled between the ends of the rails, a coupling pole fulcrumed between the coupling plates, one end of said pole being mounted to slide between the rails, a shaft journaled within the rear portions of the 10 forwardly extending strips, a cable secured to and adapted to be wound upon said shaft, said cable being extended partly around the

sheaves and secured to opposite portions of the pole, and means mounted upon the cross beam and rails for rotating the shaft, and 15 a locking device removably mounted within the forwardly extending strips and insertible into engagement with the pole to hold said pole in alignment with the strips.

WILLIAM C. LORENZ.
